UNITED STATES PATENT OFFICE.

EDWARD T. HAASE, OF ST. LOUIS, MISSOURI.

DESIGN FOR A BOTTLE.

SPECIFICATION forming part of Design No. 25,569, dated June 2, 1896.

Application filed April 27, 1896. Serial No. 589,321. Term of patent 14 years.

To all whom it may concern:

Be it known that I, EDWARD T. HAASE, a citizen of the United States, residing at the city of St. Louis, State of Missouri, have invented and produced a new and original Design for Bottles or Flasks, of which the following is a specification, reference being had to the accompanying drawings, showing a part thereof.

Figure I is an edge view of my design. Fig. II is a side view.

The leading feature of my design consists of a bottle having flat and substantially parallel side surfaces and having flat and tapering edge surfaces that form the body of the bottle. The neck of the bottle is made cylindrical and tapers to its point of junction with the body. Each side and each edge surface is formed with a panel.

1 represents the parallel side surfaces of the bottle or flask, each surface having a panel 2.

3 represents the edge surfaces of the bottle or flask, and which taper inwardly from the top toward the bottom of the bottle. These surfaces are each provided with a panel 4.

5 represents the neck of the bottle, which diverges off in all directions, as shown at 6, to where it joins with the body of the bottle.

I claim as my invention—

The design for a bottle or flask herein set forth.

EDW. T. HAASE.

In presence of—

STANLEY STONER,
W. FINLEY.
